[57] CLAIM

The ornamental design for an illuminated sculpture, as
shown and described.

DESCRIPTION

FIG. 1 is a front isometric view of an illuminated sculp-
ture showing my new design;

FIG. 2 is a back isometric view thereof;

FIG. 3 is a top plan view thereof;

FIG. 4 is a front elevational view thereof;

FIG. 5 is a back elevational view thereof;

FIG. 6 is a right side elevational view thereof; and,

FIG. 7 is a left side elevational view thereof.

The stippled surfaces of the design are translucent.

FIG. 1.

FIG. 2.

FIG. 3.

FIG. 4.

FIG. 5.

FIG. 6.

FIG. 7.
